UNITED STATES PATENT OFFICE.

JOSEPH H. WITTMANN, OF KANSAS CITY, MISSOURI.

BED.

1,415,135.

Specification of Letters Patent. Patented May 9, 1922.

Application filed September 12, 1918. Serial No. 253,715.

To all whom it may concern:

Be it known that I, JOSEPH H. WITTMANN, a citizen of the United States, residing at Kansas City, in the county of Jackson and State of Missouri, have invented certain new and useful Improvements in Beds; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to beds and one of the objects of the invention is to provide a bed structure, the bottom of which may be constructed of a flexible sheet having uniform longitudinal tension, the tension on 20 the sheet being evenly distributed throughout its width, so that when the sheet is drawn taut, the same tension will be exerted as far as practicable on each of the warp threads so that liability of the sagging of the bed 25 bottom between the longitudinal edges, will be reduced to a minimum if not wholly avoided.

Another object of the invention is to provide means whereby the length of the effective portion of the bed bottom may be decreased or diminished as occasion may demand and I further provide means whereby a variable tension may be exerted upon the bed bottom to compensate for varying 35 weights supported by said bottom.

I am aware that it is old to permanently support flexible canvas sheets or sheets of other material to apply the same as a hammock or bed but in so far as I am aware all 40 such devices have an inherent tendency to sag or permit slack which adds to the discomfort of the occupant.

I have provided means whereby substantially the entire bed bottom may be maintained in a horizontal plane without sagging so that the occupant may lie flat at all times.

For the purpose of illustration I have shown the bed attached to a motor vehicle body, its application under such circumstances being capable of convenient installation without altering the motor vehicle, and its storage when not in use requires but little space in the vehicle.

In the drawings:

Fig. I is a perspective view of a motor vehicle to which my invention is attached.

Fig. II is a fragmentary side elevational view of the motor vehicle showing the invention applied.

Fig. III is a perspective view of the bed bottom showing the slack take up bars detached, part of the fabric being broken away to illustrate one end bar of the sheet.

Fig. IV is a fragmentary longitudinal 65 sectional view through one of the slack take up bars.

Fig. V is a detail view of one of the draw-keys adapted for use in connection with my invention.

Referring now to the drawings by numerals of reference:

1 designates the bed bottom which may consist of a flexible sheet having a hem or pocket 2 at one end to receive the transversely disposed end bar 3, the hem being cut away at 4 and 5 to permit the introduction of the stays 6 which may be anchored to a suitable support, as for example, the vertical bars 7 of the windshield frame. 75 8 are slings which support the bar 3 vertically as shown. At the opposite end of the sheet is a rectangular spindle or winding bar 9 to which the end of the sheet may be appropriately attached. The ends of the 85 bar 9 are rectangular and fit in the sockets 10 and 11 of the slack take up bars 12 and 13. Each bar may be reinforced by a strap 14 and each bar may be provided with a plurality of eye-bolt receiving openings 15 into 90 which may be introduced an eye-bolt 16 adapted to be fulcrumed upon the body top rest iron 17 whereby the levers may be turned upon the axis of said iron. Secured to the levers 12 and 13, on the ends distant 95 from sockets 10 and 11 are springs 18 connected to cords or cables 19 on which are draw-keys 20 whereby the cable 19 may pass around the carriage top bow supports 21 so as to enable the draw-keys to adjust tension on the take up levers 12 and 13.

When it is desired to erect that embodiment of my invention which is capable of attachment to a motor vehicle, I may first fasten the stays 6 as shown and then attach 105 the sling straps 8. The bar 9 may be then manipulated to wind or unwind the sheet 1 accordingly to accommodate the length of

car. The eye bolts 16 may be slipped over the top rest irons and fastened in place by suitable cotter pins. The operator then passes the cable or cord 19 over the member 5 21 and through the medium of the draw-keys 20 exert the desired tension on spring 18 and through said spring and lever, the flexible sheet 1 will be drawn taut.

Inasmuch as the bars 3 and 9 extend entirely across the sheet and since each bar is fastened evenly on the sheet, a proper uniform tension may be extended throughout the bed bottom 1. If the sheet is too long, the material may be wound on the bar 9. If 15 it is desired to lengthen the sheet, the bar 9 may be removed from the sockets 10 and 11 and enough material unwound to provide the desired length. Before attaching the levers 12 and 13 to the rectangular ends of the bar 20 9, the fulcrum members consisting of the screw eye 16 may be inserted in suitable openings 15 to provide the necessary tension for a given weight. The spring supplied will usually be of a uniform scale, that is the 25 same springs will be capable of use under all conditions. As is well understood it is one of the desirable features in beds to have the requisite amount of resiliency without permitting undue sag. A bed with springs 30 sufficiently elastic to provide the requisite amount of resiliency for a light body, would be too light to support a heavy body and conversely, springs which are sufficiently rigid to provide the requisite amount of support 35 for a heavy body, will be too strong to supply the necessary resiliency for a light body. The necessary amount of resiliency as well as the necessary amount of tension is provided according to my invention by varying 40 the fulcrums of the levers 12 and 13. For example, when a heavy body is to be supported upon the bed bottom 1, the fulcrum shown as a screw eye, will be in the uppermost opening 15, thereby permitting 45 the maximum amount of leverage to be exerted by the depending ends of the levers 12 and 13. When however, a lighter body is to be supported, the screw eyes 16 may re- 50 pose in one of the lower openings 15 and as the fulcrums approach the middle of the levers, the leverage will be more evenly distributed on both sides of the fulcrums requiring less weight on the weight side of the lever to overcome the resistance on the power 55 side, therefore the required amount of resiliency will be obtainable with the body of less weight than when the fulcrums are in the uppermost openings 15.

It will be apparent that when the sheet is 60 wound or unwound from the bar 9, any further unwinding is prevented after the sockets 10 and 11 receive the ends of the bar because the bar cannot turn when the bed is set up for use.

65 It will also be observed that the device

may be set up in the quickest possible time, that after the sheet is drawn taut, the proper tension may be supplied by properly positioning the fulcrums, that when the device is not in use it may be readily disassembled 70 and made into a comparatively small package to be stored with the top curtains or in some other convenient part of the motor vehicle; the motor vehicle being the most useful embodiment of the invention known at 75 this time, although obviously the invention may partake of other embodiments.

Having thus described my invention what I claim as new therein and desire to secure by Letters-Patent, is:

80

1. In a motor vehicle bed, a sheet having means at one end for attachment to a motor vehicle, a winding bar, angular in cross section and located at the other end of the sheet, fulcrum levers having angular sockets into 85 which the ends of the winding bar engages, a fulcrum member for each lever, and yielding connections for the free ends of each lever.

2. In a motor vehicle bed, a sheet, supporting means at one end of the sheet, a winding bar angular in cross section at the other end of the sheet and upon which the sheet may be wound, detachable fulcrum levers for the bar having angular sockets into which the 95 ends of the winding bar engages, a fulcrum member for each lever, and connections for the free ends of the levers may be drawn in one direction to rock the socket members in an 100 opposite direction to impart tension to the sheet.

3. In a motor vehicle having a top and provided with top rest irons and top body supports, the combination of a sheet, means 105 for fastening one end of the sheet to the front portion of the motor vehicle above the seat back, a tension bar at the other end of the sheet, levers on each side of the vehicle and having their upper ends fastened to the 110 tension bar, means for fulcruming the levers to the top rest irons of the vehicle, and means for yieldingly connecting the lower ends of the levers to the top body supports of the motor vehicle.

115

4. In a motor vehicle having a top and provided with top rest irons and top body supports, the combination of a sheet, means for fastening one end of the sheet to the front portion of the motor vehicle above the 120 seat back, a tension bar at the other end of the sheet, levers on each side of the vehicle and having their upper ends fastened to the tension bar, means for fulcruming the levers to the top rest irons of the vehicle, and means 125 for yieldingly and adjustably connecting the lower ends of the levers to the top body supports of the motor vehicle.

In testimony whereof I affix my signature.

JOSEPH H. WITTMANN.
